UNITED STATES PATENT OFFICE.

DANIEL L. FRIDDLE, OF JACKSON, ALABAMA.

FORCE-PUMP.

SPECIFICATION forming part of Letters Patent No. 710,770, dated October 7, 1902.

Application filed April 17, 1902. Serial No. 103,334. (No model.)

To all whom it may concern:

Be it known that I, DANIEL L. FRIDDLE, a citizen of the United States, residing at Jackson, in the county of Clarke and State of Alabama, have invented certain new and useful 5 Improvements in Force-Pumps, of which the following is a specification.

This invention relates to lift or force pumps; and the object of the invention is to provide an 10 induction-block and an exhaust-block separable from each other, each block being of peculiar interior form and of such novel arrangement that the parts may be simply and quickly assembled, and special means for connecting 15 the blocks together and to a pump-cylinder.

In the accompanying drawings, forming part of this application, Figure 1 is a perspective view of my improved pump in position for operation. Fig. 2 is a cross-section of the 20 valve-blocks with pipes and rod partly broken away. Fig. 3 is a similar view in longitudinal section. Fig. 4 is a detail elevation of one of the valve-blocks. Fig. 5 is a cross-section of a modification, showing a single 25 valve-block with one of its valve-seats detachable and employing swinging flap-valves.

The same numeral references denote the same parts throughout the several views of the drawings.

30 The pump-rod 1, having a piston 2, is worked in a cylinder 3 by a suitable handle 4 and is held in vertical movable position by collars 5, secured to the pipe and having eyes 6 for said rod. This arrangement may be varied 35 as occasion may demand or according to the application of the pump, or it may be changed or dispensed with when it is desired to work the pump by steam, windmill, or other motive power than by hand. The preferred form 40 consists of rectangular blocks 7 and 8, of any suitable material, but preferably of hard wood. The induction-block 7 has a central induction-port 9, provided with a screen or strainer and terminating at the inner end in a valve- 45 seat 10, formed in the end wall 11 of a bore or cavity forming a pocket 12 for a ball-valve 13, which is loosely contained in the pocket by a bar or bars 14. A semicircular bore 15 extends from the top surface of said block to 50 the top wall of and into the pocket 12, and one of the bars 14 prevents the valve 13 from

closing said bore. It will be seen that the pocket 12 and valve-seat 10 are formed by boring into the block from the inner face thereof. The block 8 is the same size and 55 shape of the block 7 and has an exhaust or water-discharge port 16 in its inner face and terminating at the inner end in a valve-seat 17, formed in the end wall 18 of a valve-pocket 19. This port, valve-seat, and pocket are formed 60 by boring into the block 8 from the outer face thereof. A semicircular bore 20 is made through the top of the block 8 into the opening of the valve-seat 17, and the ball-valve 21 is loosely held in the pocket 19 by a bar 65 22. In this block 8 it will be observed that the bore 20 does not communicate with a pocket as the like bore of the other block, except through the valve 21. The blocks 7 and 70 8 are assembled with their inner faces engaging, so that the exhaust-port of one block will be opposite the pocket of the other block and the two semicircular bores will form a circular communication for the pipe or cylinder 3. The cylinder 3 has a flange 23 secured 75 to the blocks by bolts 24, passed through and between the blocks, with a gasket between the blocks and the flange.

The exhaust-pipe 1^a is provided with a flange 25, secured to the block 8 over the 80 pocket 19 by means of bolts 26, with a gasket 27 between the block and the flange, and said bolts extend through both blocks at right angles to the bolts 24 to secure the blocks firmly together. A gasket 28 may be 85 used between the blocks if desired.

Referring to the modification shown in Fig. 5, a single block is employed, having pockets 29 and 30, the latter being provided with a detachable valve-seat or end wall 31, having 90 a valve-seat and a flat hinged valve 32, and the pocket 29 has a like valve 33. In this form the vertical and horizontal bolts are dispensed with; but with this exception and those above noted the device is the same as 95 that first described.

It is obvious that when the blocks are immersed, or partially so, in water and the pump-rod worked such working will open and close the ball-valves and permit a continuous 100 stream of water through the ports.

Having thus described my invention, what

I claim as new, and desire to secure by Letters Patent, is—

In a force-pump, the combination, with the cylinder, the induction-block having a lateral bore terminating in a valve-seat, a semicircular vertically-disposed bore terminating in the pocket, a ball-valve loose in the pocket, and a bar at the intersection of the pocket and the vertical bore to confine the ball and prevent its closing the said bore, of the exhaust-block separable from the induction-block and having a valve-seat next to the said pocket, a semicircular vertical bore ter-

minating at said valve-seat, a pocket extending outwardly from this seat and containing a ball-valve, the bolts securing the blocks together, and the bolts for connecting the blocks in a pair to the pump-cylinder, substantially as set forth.

In witness whereof I hereunto set my hand 20 in the presence of two witnesses.

DANIEL L. FRIDDLE.
